UNITED STATES PATENT OFFICE.

JOHN C. DELL, OF PHILADELPHIA, PENNSYLVANIA.

GEARING FOR GRINDING OR OTHER MILLS.

SPECIFICATION forming part of Letters Patent No. 743,256, dated November 3, 1903.

Application filed October 23, 1902. Serial No. 128,420. (No model.)

To all whom it may concern:

Be it known that I, JOHN C. DELL, a citizen of the United States, residing in the city and county of Philadelphia, State of Pennsylvania, have invented new and useful Improvements in Gearing for Grinding or other Mills, of which the following is a specification.

My invention consists of an improvement in gearing for a grinding or other mill adapted to operate by the rapid motion of a dynamo or other suitable power wherein provision is made to slow up the shaft of said mill, and thus prevent injury to the mill which would be occasioned should said shaft run with the rapidity of its prime motor.

Figure 1 represents a side elevation of a grinding-mill embodying my invention. Fig. 2 represents a vertical section of a portion thereof.

Similar letters of reference indicate corresponding parts in the figures.

Referring to the drawings, A designates the casing of a grinding-mill, and B the driving-shaft thereof, said shaft being supported on the bearings C C', which, with the bearing C², are all common to the base C³ and rigid therewith, as seen best in Fig. 1. By this means I provide an attachment which can be readily moved to the store or other place of use, and by removing the shaft of the grinding-mill there existing and applying the elongated shaft B herein shown the old mill need not be dispensed with or thrown away, but can be used in conjunction with the improved base and its bearings and the driving mechanism hereinafter described.

D designates a spur-wheel which is secured to the shaft B and meshes with the pinion E, to whose side or hub is secured the spur-wheel F, said pinion E and spur-wheel F being mounted on the counter-shaft G, which is supported on the bearings C and C² parallel with the shaft B. The shaft G is free within the pinion E and spur-wheel F and the sleeve intermediate the same, one end being disposed within a socket on the inner side of the bearing C and at the other end in a boss C⁴, projecting from the bearing C². A suitable fastening C⁶—such as a screw, pin, or any analogous means—is applied to retain the shaft in place. The end of the shaft G projects beyond the base, so that when the fastening is removed

the said shaft may be grasped and withdrawn, thus permitting of the ready removal of the pinion and spur-wheel and dismembering of the parts.

H designates a pinion which meshes with the wheel F and has its hub J mounted loosely on the extended portion K of the shaft B, said hub having secured to it the driving-pulley L.

The operation is as follows: The pulley L is adapted to receive rapid motion from a dynamo or other electric power or other rapid prime motor, if so desired. This rapidity would be injurious, if communicated to the shaft B, in many ways, such as excessive vibrations of the mill, strain on the parts, quick wearing away of the same, improper grinding, &c.; but this is obviated by the motion of the pulley being transmitted to the pinion H, then to the large spur-wheel F, then again to pinion E and the larger spur-wheel D, and thus to the driving-shaft B, which is thus run with sufficient power to properly cause the grinding action of the machine, but with reduced rapidity, the advantages of which are evident.

Having thus described my invention, what I claim as new, and desire to secure by Letters Patent, is—

1. In a grinding or other mill, a driving-shaft, a driving-pulley, an endwise-removable counter-shaft, gears on said driving-shaft and counter-shaft respectively, a second gear on the counter-shaft, and a gear movable with the driving-pulley and meshing with the second gear on the counter-shaft, said gearing being non-shiftable and said shafts being mounted in fixed bearings and one of the bearings for the counter-shaft being a socket closed at its outer end and the pulley adapted to be rapidly driven whereby said driving-shaft receives the power of the pulley with reduced speed.

2. In a grinding or other mill, a base, bearings rising therefrom, one of said bearings being formed with a socket upon its inner side and the other with a boss, a pinion and a spur-wheel, an intermediate sleeve disposed between said wheel and pinion and a shaft removably engaged within and free of said pinion, wheel and sleeve, with one end mounted in said socket and the other in said boss, a driving-shaft and operative connec-

tions between the same and said pinion and spur-wheel.

3. In a grinding or other mill, a base, bearings rising therefrom, one of said bearings being formed with a socket upon its inner side and the other with a boss, a pinion and a spur-wheel and an intermediate sleeve disposed between said wheel and pinion, a shaft removably engaged within and free of said pinion, wheel and sleeve, with one end

mounted in said socket and the other in said boss, said shaft projecting at one end beyond said boss, means for retaining said shaft in position, a driving-shaft and operative connections between the same and said pinion and spur-wheel.

JOHN C. DELL.
